(57) CLAIM

The ornamental design for a case and attached belt for a portable music player, as shown and described.

DESCRIPTION

FIG. 1 is a front perspective view of a case and attached belt for a portable music player, showing the new design with environment, the broken lines forming no part of my claimed design;

FIG. 2 is a rear elevation view of the invention illustrated in FIG. 1 shown in a closed position;

FIG. 3 is a left elevation view of the invention illustrated in FIG. 1;

FIG. 4 is a front elevation view of the invention illustrated in FIG. 1;

FIG. 5 is a right elevation view of the invention illustrated in FIG. 1;

FIG. 6 is a top plan view of the invention illustrated in FIG. 1; and,

FIG. 7 is a bottom plan view of the invention illustrated in FIG. 1.
